WRINGER MOP

Samuel J. Popeil, Chicago, Ill., assignor to Popeil
Brothers Inc., Chicago, Ill.

Filed June 11, 1971, Ser. No. 152,477

Term of patent 14 years

Int. Cl. D4—01

U.S. Cl. D49—21

FIG.5

FIG.2

FIG.1

FIG.3

FIG.4

FIG.6

FIG. 1 is an elevational view of the subject wringer mop with the offset handle extending from right to left as viewed in the accompanying drawings.

FIG. 2 is a side edge elevational view taken in the direction of the arrows along the line 2—2 in FIG. 1, showing the seamed edge along the length of the mop handle.

FIG. 3 is a side edge elevational view taken in the direction of the arrows along the line 3—3 in FIG. 1, showing the opposed side edge of the wringer mop from top to bottom as distinguished from FIG. 2.

FIG. 4 is an elevational view of the wringer mop showing the reverse side thereof as opposed to the view shown in FIG. 1.

FIG. 5 is a top view of the wringer mop showing the disposition of the offset handle.

FIG. 6 is a bottom view of the wringer mop.

I claim:

The ornamental design for a wringer mop, as shown and described.
